UNITED STATES PATENT OFFICE.

PHILLIP JACOBS, OF BONHAM, TEXAS.

COMBINED WHIP-SOCKET AND REIN-HOLDER.

SPECIFICATION forming part of Letters Patent No. 790,503, dated May 23, 1905.

Application filed October 19, 1904. Serial No. 229,191.

To all whom it may concern:

Be it known that I, PHILLIP JACOBS, a citizen of the United States, residing at Bonham, in the county of Fannin and State of Texas, have 5 invented new and useful Improvements in a Combined Whip-Socket and Rein-Holder, of which the following is a specification.

My invention pertains to combined whip-sockets and rein-holders; and it contemplates 10 the provision of such a device in which the placing of the reins in the holder will automatically lock the whip in the socket, while the removal of the reins will assure the release of the whip and leave the same free for 15 an emergency, and one which is a material simplification of combined whip-sockets and rein-holders extant and embodies no delicate parts such as are likely to get out of order after a short period of use.

With the foregoing in mind the invention 20 will be fully understood from the following description and claims when taken in connection with the accompanying drawings, forming part of this specification, in which—

Figure 1 is a perspective view illustrating 25 the application of the device constituting the present and preferred embodiment of my invention to the dashboard of a vehicle and the use of the said device in holding a whip and 30 reins or driving-lines. Fig. 2 is an enlarged vertical central section taken through the combined whip-socket and rein-holder, and Fig. 3 is a transverse section taken in the plane indicated by the line 3-3 of Fig. 2 looking 35 downwardly.

Similar letters designate corresponding parts in all of the views of the drawings, referring to which—

A is the socket of the combined device. 40 The said socket, which may be of light sheet-metal or any other material compatible with the purposes of my invention, is peculiar in that it is provided in its side with an opening a.

B is the rein-holder of the device. This 45 rein-holder B comprises an outer member b and an inner member c. The outer member is preferably of stiff tempered steel and has a lower straight portion d, riveted or other-

wise fixed to the side of the socket below the 50 opening a, an outwardly and upwardly bent intermediate portion e, and an upper free portion f, the upper end of which is flared, as shown, to facilitate the interposition of the reins between the members. The inner member 55 is preferably of light steel, and hence is quite resilient or springy. It is riveted or otherwise connected at its upper end to the side of the socket A, is bent outwardly adjacent to its lower end, as indicated by g, and 60 is provided at said end with an inwardly-directed portion h, which extends through the opening a in the side of the socket A, and is provided, by preference, with a concave inner end i.

I prefer to employ in the socket A a bowed spring G, Fig. 2, which is disposed diametrically opposite the rein-holder B and has for its purpose to assist in holding a whip in the socket when the reins are removed from their 70 holder and also when the reins are in the holder.

In the practical use of my novel device it will be seen that when a whip is in the 75 socket A and reins or driving-lines are placed in the holder B, as by a person leaving a vehicle, the inner member c of the said holder B will be forced inwardly, and hence will bind against the whip and lock or secure the same in the socket A and against casual removal or 80 displacement. It will also be seen that when the reins are removed from between the members of the rein-holder the inner member c will spring outwardly to its normal position, thereby leaving the whip free to be removed 85 from the socket A when occasion demands.

From the foregoing it will be gathered that the placing of the reins in the holder B effects the locking of the whip in the socket, while the removal of the reins is attended by the 90 automatic release of the whip. From this it follows that when the reins are in use the whip is ready for any emergency that may arise. This latter will be appreciated as an important advantage when it is remembered 95 that in those combined whip-sockets and rein-holders in which the whip is locked or secured independently of the reins a driver in

taking up the reins frequently fails to unlock or release the whip, and hence the whip is not available for use in the event of the animal or animals that are being driven becoming fractious.

It will be understood from the foregoing that my novel combined device is not only automatic and reliable in use, but is simple and inexpensive in construction and well adapted to withstand the usage to which combined whip-sockets and rein-holders are ordinarily subjected.

I have entered into a detailed description of the construction and relative arrangement 15 of the parts embraced in the present and preferred embodiment of my invention in order to impart a full, clear, and exact understanding of the said embodiment. I do not desire, however, to be understood as confining myself to such specific construction and relative arrangement of parts, as such changes or modifications may be made in practice as fairly fall within the scope of my invention, as claimed.

Having described my invention, what I claim, and desire to secure by Letters Patent, is—

1. The combination of a whip-socket having an opening at its side wall, and a rein-holder 30 comprising an outer member having a lower portion connected to the outer side of the side wall of the socket, below the opening therein, and extending upwardly outside of the socket, and an inner spring member arranged between the outer member and the outer side of the side wall of the socket, connected to the socket, above the opening in the wall thereof, and having an inwardly-directed portion ar-

ranged to pass through the said opening in the wall of the socket.

2. The combination of a whip-socket having an opening in its side wall, and a rein-holder comprising an outer member having a lower portion fixedly connected to the outer side of the socket below the opening therein, and also having an outwardly and upwardly extending intermediate portion and an upper free portion, and a spring member arranged between the outer member and the outer side of the socket and fixedly connected to the socket above the opening therein and having an inwardly-directed portion arranged to pass through the said opening in the socket.

3. The combination of a whip-socket having an opening in its side wall, a bowed spring 55 arranged in the socket diametrically opposite the said opening, and a rein-holder comprising an outer member having a lower portion connected to the outer side of the side wall of the socket, below the opening therein, and extending upwardly outside of the socket, and an inner spring member arranged between the outer member and the outer side of the side wall of the socket, connected to the socket, above the opening in the wall thereof, 60 and having an inwardly-directed portion arranged to move inwardly and outwardly in the said opening in the wall of the socket.

In testimony whereof I have hereunto set my hand in presence of two subscribing witnesses.

PHILLIP JACOBS.
